UNITED STATES PATENT OFFICE.

ENOS O. VANN, OF PUEBLO, COLORADO.

LOCK.

1,027,940.

Specification of Letters Patent.

Patented May 28, 1912.

Application filed August 9, 1911. Serial No. 643,102.

To all whom it may concern:

Be it known that I, ENOS O. VANN, a citizen of the United States, residing at Pueblo, in the county of Pueblo and State of Colorado, have invented new and useful Improvements in Locks, of which the following is a specification.

This invention relates to locks and more particularly to coin controlled locks.

10 One of the principal objects of the invention is the provision of a lock of this character having means whereby the key may be withdrawn from the lock only by a coin being used of the proper denomination.

15 A further object of the invention is the provision of a combined key and coin controlled mechanism for securing the lock against operation until a coin of the proper denomination is used in connection with the key, so as to prevent the release of the locking mechanism and the locking of the lock. It will be understood that this type of lock is especially adapted for use in connection with lockers and the like in public places where 20 a person can deposit any articles and, by using a coin of the proper denomination, can operate the lock to lock the cupboard or locker and then obtain the key for opening the same when it is desired to remove the 25 articles. The operation of unlocking the lock automatically secures the same in unlocked position and holds the key against removal until another coin is deposited.

Further objects of the invention will appear as the following specific description is read in connection with the accompanying drawings, which form a part of this application, and in which:—

Figure 1 is a rear elevation of the device 40 shown attached to a door, the dot and dash lines in all the figures indicating the door. Fig. 2 is a top plan view. Fig. 3 is a vertical sectional view showing the key in locked position. Fig. 4 is a similar view 45 showing the key in position to be released. Fig. 5 is a sectional view on the line 5—5 of Fig. 3. Fig. 6 is a similar view on the line 6—6 of Fig. 4. Fig. 7 is a perspective view of the locking member.

50 Referring more particularly to the drawings, 1 represents a door to which the front plate 2 of the lock is secured in any suitable manner. This lock carries a casing 3 and in the casing is mounted the ordinary bolt 4 and tumbler controllers 5. The lock has a cylinder extension 6 which projects through

the front of the door and, mounted in the cylinder, is a key plunger 7 slotted at 8 to receive a key 9.

An auxiliary casing 10 is mounted upon 60 the cylinder and connected to the front plate and has secured therein a spring 11 having a cam outer face 12 adapted to be engaged by the key for depressing the spring. The spring passes through a slot 13 in the cylinder 6 and is adapted to enter the slot 8 when the key 9 is removed therefrom, so as to hold the plunger in position against turning until the key is inserted, which action depresses the spring and permits rotation of 70 the plunger and the retraction of the bolt 4.

The casing 10 is provided with an extension 14 which is raised from the plate 2 and is of such a width as to permit one leg 15 of a U-shaped locking member 16 to slide therein. The leg 15 of the locking member has its lower end reduced, as shown at 17, to pass through an opening 18 in the casing 6 and enter an arcuate slot 19 formed in the plunger and having shoulders 20 at the ends 80 thereof. The opposite end of the locking member 16 is indicated at 21 and lies upon the inside of the casing 3 and is parallel with the leg 15, the locking member passing through a slot 22 in the plate 2 which is 85 coincident with the channel in the extension 14 of the casing 10.

The lower end of the leg 21 is provided with an arcuate finger 23 against which the coin, indicated at 24, is adapted to rest. 90 When in operative position the coin is positioned between the finger 23 and the projecting end 25 of the key 9. This projecting end is made somewhat wider than the ordinary keys of this type so that when the 95 key is turned in the lock the length of the slot 19 it will raise the coin a sufficient distance to release the reduced end 17 from the opening 18. The locking member 16 is normally forced downwardly by a leaf spring 100 26 which is secured to the front plate and lies over the top or connecting portion of the lock member.

When the key is placed in the lock and displaces the spring 12 the plunger 7 may be turned to the position shown in the Figs. 3 and 5 where it will abut one end of a stop 27 carried by the cylinder 6. In this position the leg 15 of the locking member will have its reduced end 17 entered in the socket 110 or channel 18 so that the plunger is positively prevented from turning, except for a

short distance. When a coin is inserted in the deposit chute 28 it passes through the same and rests upon the flat side of the key extension 25 and is held in such position by 5 the finger 23 which it lies beneath. Upon turning the key the extension 25 will raise the coin and consequently the locking device 16 and thus release its reduced end from the channel 19. This action takes place before 10 the shoulder 20 comes in contact with the pin 17. The key may then be turned entirely around to the position shown in Fig. 4, where it is released from the flange 29. When the key is in this position it is engaged with the opposite end of the stop 27 and the guiding or positioned ward is released 15 from the flange 29 and the key in alignment with the slot 31, formed in the flange 29. After the key has been turned around 20 so as to align with the slot 31 and removed from the plunger, the coin drops into a coin chute 32. This chute 32 is carried by a casting 33 which covers the locking member 16 and the remainder of the lock and is provided with a door 34 in its bottom which 25 closes the money pocket 35 therein and is provided with a separate lock 36 by which the door is fastened. This lock 36 is controlled only by the pass key which is carried 30 by the owner or agent of the person owning the lockers.

Having thus described the invention, what I claim as new is:—

1. In combination, a lock having a bolt, 35 and a slotted key plunger, means for securing the key plunger against turning in a direction to project the bolt, means for holding a coin, and a key for throwing the securing means to inoperative position 40 through the intermediary of a coin and for projecting the bolt said key directly engaging the coin.

2. In a device of the class described, a lock including a bolt, a key for projecting 45 and retracting said bolt, means to secure the bolt against projection, and an operative connection between the key and the securing means including a coin directly engaged by the key whereby when the key is

initially operated the securing means will 50 be thrown to inoperative position and upon further movement of the key the bolt will be projected.

3. In combination, a lock having a bolt, 55 means to lock the bolt against projection, a key for operating the lock, and means for supporting a coin on the key and between the same and the locking means thereby producing an operating connection.

4. In combination, a lock having a bolt, 60 means to lock the bolt against projection, a key for operating the lock, and means carried by the locking means for supporting a coin on the key between the same and the locking means, thereby producing an operating 65 connection.

5. In combination, a lock having a key projected bolt and a slotted key plunger, an apertured casing surrounding the key plunger, a locking member passing through the 70 aperture, means for normally holding the locking member in the slotted key plunger, a key for operating the lock, means to hold a coin on the key, said key supporting the coin and raising the same when operated to 75 throw the bolt, and means actuated by the coin for raising the locking member out of the slot.

6. The combination with a lock casing having a flanged cylinder thereon, a key 80 slotted plunger mounted for rotation in the cylinder, a key adapted for operation in the key plunger and having a ward to be engaged by the flange on the key cylinder, means for locking the key plunger with the 85 ward in engagement with the flange, a key for operating the lock, and means to hold a coin interposed between the key and the locking means, whereby when the key is operated the locking means will be released 90 from the key plunger.

In testimony whereof I affix my signature in presence of two witnesses:

ENOS O. VANN.
